GAME

Thomas De Lorenzo, West Medford, Mass.

Application January 29, 1940, Serial No. 316,135

5 Claims. (CL. 273—14)

This invention relates to games and particularly to a parlor game for two players consisting of a rectangular game board having side walls and a goal at one end and a rotatable spinning ring near its opposite end on a division line extending transversely of the upper face of said board, and through which a playing ball is adapted to be projected.

One object of the invention is to provide said spinning ring with suitable markings on the front face thereof, indicating the correct side through which the playing ball should be projected.

Another object of the invention is to provide two balls of different colors, one for each player, whereby each player may recognize his own ball wherever it may be positioned on the game board.

A further object of the invention is to provide means whereby these playing balls may be projected toward the head of the game board in an effort to pass them through the spinning ring.

A further object of the invention is the provision of means whereby the spinning ring may be rotated about its vertical axis so that when it comes to rest the front side thereof may face in most any direction, thereby complicating the playing of the game.

These objects are all accomplished by the instrumentalities illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawing:

Figure 1 represents a game board embodying the principles of the present invention.

Figure 2 represents a section of a portion of the same on line 2, 2 on Fig. 1 and drawn to an enlarged scale, showing the means of supporting a spinning ring on said board.

Figure 3 represents a modified form of the means for supporting the spinning ring.

Figure 4 represents another modified form of means for supporting the spinning ring.

Figure 5 represents an elevation of one of the balls used in playing the game.

Figure 6 represents a detail of the side walls

of the game board and showing a rubber cushion on the inner face thereof, and

Figure 7 represents a cue or similar device which may be used in propelling the playing ball.

Similar characters indicate like parts throughout the several figures of the drawing.

In the drawing, 10 represents a flat game board having side and end walls 11 extending upwardly therefrom.

On the under side of the game board 10 are 10 a plurality of supports 12 shown only in dotted lines, these supports preferably being of rubber or some other resilient material whereby the board may be supported on a dining room table without scratching or marring the same.

The inner face of each side and end wall 11 may have secured thereto a resilient cushion 13 similar to that used in any billiard table.

Near the rear end of the board 10 is a division line 14, the object of which will be hereinafter explained.

Near the forward end of the game board 10 is a goal line 15 and on this line are two separated goal markers 16.

Two balls 17 are used in playing the game, 25 these balls being of different colors.

In playing the game these balls 17 may be propelled along said board 10 by means of a cue 18 or some similar device.

Centrally disposed on the division line 14 is 30 a socket 18 adapted to receive the shank 19 on a metal ring 20.

This shank 19 is freely revoluble in the socket 18.

The front face of the ring 20 is provided with 35 distinguishing markings such as the crosses 21, while the rear face of the ring has no such markings.

The socket 18 may be formed in the flanged member 22 nailed to the under side of the game 40 board 10, as indicated at 23, in Fig. 2.

The board 10, however, may have a cylindrical opening 24 therein as shown in Fig. 4, in which opening is positioned a tubular member 25 having projections 26 thereon extending into the board 10 to prevent the rotation of said tubular member.

The inner wall of this tubular member 25 forms a socket 18 to receive the shank 19 of the ring 20.

In Fig. 3 is shown another modification of the 50 means for supporting the ring 20.

In this construction a plate 27 provided with projections 28 on the under face thereof is forced into a depression 29 in the upper face of the board 10, and the base portion 30 of the ring 55

55

20 is provided with annular grooves 31 in which are disposed balls 32.

The ring 20 is retained in position on the board 10 by means of the cylindrical member 33 having a reduced projection 34 threaded to said board, the upper end of the cylindrical member 33 having a head 35 preventing the displacement of said ring.

Around the shank 19 of the spinning ring 10 20, the upper face of the board 10 is chamfered off as indicated at 36 in Fig. 1, thereby providing means whereby the ring 20 may freely rotate about its axis during the playing of the game.

Each playing ball 17 has a diameter considerably less than the diameter of the inner wall of the spinning ring 20.

When the game is being played it is desired that the ball 17 may freely pass through the ring 20 and consequently the inner wall of said ring 20 has a flattened portion 37 in the same plane as the upper face of the board 10.

The game usually is played by two players, one player taking a ball 17 of one color, while the other player takes a ball having a different color, so that during the game each player knows his own ball wherever it may be on the game board.

In playing the game the spinning ring 20 is first positioned with its front or marked face facing 30 toward the goal.

The players during the starting of the game are at the forward end of the game board and propel the balls toward the spinning ring 20.

The first player rolls his ball by hand toward 35 the spinning ring 20 for position, but the ball must cross the division line 14, or touch the spinning ring 20. Failing to do this, he must make a fresh start.

After the ball of the first player comes to rest, 40 the second player rolls his ball at will. If the ball at this time passes through the ring, it would not count a point toward game.

After each player has rolled his ball, the game 45 really commences by each player using a cue to propel the ball.

If the spinning ring has been rotated by being hit by a propelled ball of the first player, and the ball of the second player passes through 50 the ring from the back side thereof, the passage of the ball in this direction is what, in the game, is called a "witch" and the player scores a penalty.

When the player has a penalty due to passing 55 the ball through the ring from the rear side thereof, he cannot receive any further points in the game until he has removed this penalty by causing his ball to pass correctly through the ring 20 from the front side.

The game can be played continuously, or can 60 be started over again every time a player scores, until twelve points are scored. The player first making twelve points wins the game.

The game proceeds by each player endeavoring 65 to put his ball in position to score, and furthermore, each player endeavors to disturb the opponent's ball or the ring in order to prevent him from scoring by passing the ball correctly through the ring.

If the ball of either player comes to rest in a 70 position where it would be easy for him in his next play to correctly force the ball through the spinning ring, the other player endeavors to hit the ball and move it out of position.

If the spinning ring 20 comes to rest with

its front marked face toward the rear of the game board, a player may endeavor, by means of a carom shot, to hit a side wall, changing the direction of a ball so that it will pass correctly through the ring.

In the playing of a game, a "hit" counts two points, and is only made when a player hits the opponent's ball and then crosses the goal line 15. A "hit" can only be made when the balls are at least one foot apart, when one ball 10 is propelled in the direction of the other ball.

Three points can be scored at one time by making a "hit" and at the same time passing the ball through the right side of the ring.

As has been heretofore stated, either of the 15 players passing the ball through the wrong side of the ring 20, scores as a "witch" or penalty, and the penalty must be removed before he can score again.

The only way the penalty can be removed is 20 by a player passing a ball through the right side of the ring. In doing this, no point is made, the passing of the ball through the right side of the ring simply removing the "witch" or penalty, after which the player is free to score 25 again.

If a player can cause his ball to hit an opponent's ball and pass it through the wrong side of ring 20, it is advantageous because the player whose ball has been hit is penalized and the 30 penalty must be removed before he can score again.

In playing the game, it is sometimes very desirable for one player to note where the ball 35 of the other player is and then endeavor to hit the side of the spinning ring and cause it to rotate into a position where it would be almost impossible for the other player to pass his ball through the right side of the ring.

As the game continues, each player takes his 40 turn, always making moves either to have his own ball pass correctly through the spinning ring or trying to make a "hit" by hitting the opponent's ball and causing his own ball to pass through the goal line 15 between the goal markers 45 16.

No count is made when the ball passes over the goal line 15 between a goal marker 16 and a side wall 11.

The game is divided into periods and each 50 period ends as a "hit" is made or a "ringer" is made, the "ringer" consisting in passing the ball correctly through the spinning ring. After each period the players start over again as previously 55 described.

In the next period, the player that makes a point or points, plays first and the balls must not be touched by hand until a player scores.

The boards may be of any size either for use 60 on dining room tables or a billiard table may be utilized by providing the necessary goal lines at one end of the board, and providing means for positioning the spinning ring at a point near the opposite end of the board.

When a propelled ball hits the side of the spinning ring 20 it will cause the ring to rotate about its axis and it will be necessary to wait until the ring comes to rest before the game can continue.

When the ring is spun around its axis as just described, there is no knowing just where it will stop. Its front face may be towards one of the side walls, one of the end walls, or at an angle to these walls.

5 In view of this fact the game may be made very interesting and amusing, as under such conditions it requires considerable skill to direct the playing ball so it will pass through the ring from the front side thereof. The game may be played by two teams, each team using the same ball.

10 It is believed that the operation and many advantages of the invention will be understood without further description.

Having thus described my invention, I claim:

1. In combination with a flat rectangular game board having side walls surrounding the edges thereof, a spinning ring vertically mounted on 15 edge near one end thereof and revoluble about a vertical axis, the opening in said ring being so constructed and arranged as to permit the passage therethrough of a playball propelled over the surface of said board.
- 20 2. The combination as set forth in claim 1, in which the inner surface of the ring has a flattened portion in the same plane as the upper face of the game board.

3. The combination as set forth in claim 1, in which said ring is provided with a cylindrical shank radiating from its periphery and said board is provided with a vertical socket to receive said shank.

4. The combination as set forth in claim 1, in which said ring is provided with a cylindrical shank radiating from its periphery and said board is provided with a vertical socket to receive said shank, said socket having at its lower 10 end a flange secured to the under side of said board.

5. The combination as set forth in claim 1, in which the periphery of the ring is provided with a cylindrical base, a cylindrical plate set into 15 the upper face of the board, anti-friction members between said base and plate, and a headed cylindrical member extending through the center of said base and secured at its lowest end to said board.
